[57] CLAIM

The ornamental design for a terminal post, substantially
as shown.

DESCRIPTION

FIG. 1, FIG. 2, FIG. 3 and FIG. 4 are views of the sides
of a terminal post showing my design;

FIG. 5 is a top view; and

FIG. 6 is a bottom view with numbered arrows indicating
the corresponding sides to those shown in FIGS. 1,
2, 3 and 4.
